PORTABLE BLOWTORCH AND THE LIKE

Louis A. Falligant, Madison, Wis., assignor to
 Prepo Corporation, Edgerton, Wis., a corpora-
 tion of Delaware

Application October 30, 1950, Serial No. 192,915

13 Claims. (Cl. 158—33)

1

This invention relates to small portable torches and the like utilizing self-pressurizing inflammable liquid fuels in replaceable expendable cartridges.

The invention primarily applies to a blowtorch construction utilizing such fuel cartridges, although several features of the invention are applicable to other types of portable burners such as cigarette and cigar lighters, camp stoves and lanterns, and the like.

Blow torches heretofore have required the use of dangerous fuels such as gasoline with air pressure in the fuel container, or high pressure liquified gases such as propane and butane which had to be confined in heavy walled cylinders requiring return for refill purposes and making it impractical to throw away the cylinder when emptied.

The present invention provides a lightweight dispensable fuel cartridge for blow torches and which greatly improves the safety of blow torch operations by avoiding explosive mixtures of fuel and air within the container. The cartridge contains a low pressure fuel which enables the use of lightweight thin-walled inexpensive containers of sufficient capacity for satisfactory blow torch operations. Such a fuel cartridge has been described and claimed in copending application Serial No. 46,917, filed by the present inventor on August 30, 1948, now abandoned in favor of application Serial No. 324,890, filed on December 9, 1952, as a continuation-in-part of said earlier application.

The fuel employed in the cartridge is a hydrocarbon blend of butane and pentane in liquid form blended together in such a manner as to be substantially free from undue separation of the liquid constituents by stratification.

The butane constituents have a vaporization or boiling point substantially below normal room temperatures and which boiling point is raised to about 38° F. in the blend. The pentane constituents have a vaporization or boiling point substantially above normal room temperatures and which boiling point is lowered to about 85° F. in the blend. When the fuels are blended homogeneously both the butane and pentane constituents will vaporize throughout the range of from 38° to 85° F., under atmospheric pressure conditions, the amount or proportion of vaporization of the constituents varying with a change in temperature within the range so that 38° F. is the initial boiling point for the blend and 85° F. is the final or end boiling point for the blend. Such a fuel raises certain problems in burning when in containers of reasonable capacity for blow torch use due to the tendency of the

2

fuel to vaporize unevenly, i. e., the lower fraction or butane content having the lower boiling point tends to evaporate first leaving the pentanes of higher boiling point and which will not supply adequate starting gases at normal room temperatures.

10 The present invention centers around a combined construction with such a fuel cartridge whereby the gaseous fuel supplied to the burner is always of substantially the same composition. This has a very substantial advantage in maintaining constant burner efficiency without requiring an operator's frequent adjustment of air-fuel ratios to assure efficient operation. Less expensive burners can be employed without provision for air variation and the desired burner temperature is always present. Since the fuel is always of constant value the problems encountered of varying fuel quality as in gasoline 20 torches are avoided.

In carrying out the invention the liquid fuel is withdrawn in liquid state from the fuel cartridge and the vaporization zone is maintained in the passage leading to the burner whereby 25 all fractions of the fuel are vaporized simultaneously and the gas is then passed to the burner where it first encounters air entering through fixed air ports to provide a substantially constant fuel-air ratio designed for the most efficient combustion of the specified fuel.

The manual manipulation of the torch by grasping of the fuel container by the operator remains important in cold weather to assure a proper pressure within the container for the discharge of liquid fuel therefrom. For stoves and other burners the fact that the cartridge may be grasped by the hand and generally warmed prior to its assembly in the stove tends to provide the desired initial pressure.

40 Additional problems of providing adequate gaseous fuel at the burner for starting without the heat priming usually accompanying the gasoline torches have been solved by the present invention by employing valve means that initially 45 limits the flow of liquid fuel to the torch for starting with a blue flame and thereafter opens wide to full torch on position.

The invention avoids dangers arising from the use of excessive fuel pressures since the pressure head within the fuel cartridge or container is maintained nearly constant.

Where quick action and substantial heat is required, the invention employs a regenerative type of burner in which the fuel passage is heated 55 by the burner on its way to the fuel orifice or port in the burner. Other means of utilizing burner heat for fuel vaporization are provided

by a special passage construction to give greater heat input to the fuel in the vaporization zone.

The accompanying drawings illustrate the invention as applied to a blow torch structure and which constitutes the best mode presently contemplated for carrying out the invention.

In the drawings:

Figure 1 is a perspective view of the torch in substantially side elevation;

Fig. 2 is a similar view showing the several assembly parts exploded in non-assembly;

Fig. 3 is an enlarged detail view of the bottom clamp and torch support showing its operation;

Fig. 4 is an enlarged detail view showing the cartridge holder in vertical central section and with the cartridge and valve assembly in elevation and partly in section;

Fig. 5 is an enlarged fragmentary central section through the upper end of the cartridge showing the closure construction;

Fig. 6 is a top plan view of the cartridge of Fig. 4;

Fig. 7 is an enlarged detail central section through the valve assembly;

Fig. 8 is an enlarged detail central section through a modified form of valve assembly;

Fig. 9 is an enlarged detail central section through the burner assembly;

Fig. 10 is an enlarged detail central section through a modified form of burner assembly;

Fig. 11 is an enlarged view partly in section of the lower end of the burner tube showing the filter construction; and

Fig. 12 is an enlarged partial view of the throttle valve of Fig. 7.

The torch comprises, in general, a cartridge holder or shroud assembly 1 adapted to have a fuel cartridge 2 assembled therewith, a valve assembly 3 and a burner assembly 4.

The cartridge holder or shroud assembly 1 comprises a circular base 5 hinged at one side to a vertical strap 6 extending rigidly downwardly from an upper circular shroud 7 secured to the valve body 3, and a second vertical strap 8 hinged at its upper end to the shroud 7 on the side opposite strap 6 and having an inwardly extending spring clamp end 9 adapted to lock the base 5 against the bottom of a cartridge 2.

The vertical straps 6 and 8 generally follow the side contour of the cartridge 2 and leave the major portion of the cartridge exposed for grasping by the hand in manipulating the torch.

The clamp 9 is connected to strap 8 by a reverse bend in the strap and which snaps the strap tightly in place when assembled with base 5 and with a cartridge 2 in place.

The base 5 has a recess 10 in one side disposed to receive the clamp 9 when the latter is manually closed beneath the base and cartridge.

The holder 1 is quick to operate in securing a cartridge in place and in releasing the cartridge.

The cartridge 2 comprises a metal can 11 designed to withstand a fuel pressure as high as about three hundred pounds per square inch, which provides a high factor of safety for all normal operating conditions.

The fuel in cartridge 2 is preferably a blended butane-pentane fuel of approximately the following composition:

Per cent by weight

Normal butane	52.3
Isobutane	2.2
Isopentane	43.5
Normal pentane	2.0

The above fuel has a vapor pressure not exceeding 33.6 pounds per square inch, absolute, at a temperature of 100° F., and the fuel is classified for transportation and handling purposes as an inflammable liquid, and not as a liquified petroleum gas. The blend and composition may vary so long as the self-pressurizing characteristics of the fuel do not take it into the ranges of liquified petroleum gas classifications by safety and regulatory bodies and thereby subject the torch and the fuel cartridges to laws and regulations that prohibit the practical use of the same. By staying within the inflammable liquid class, and keeping the cartridges within a certain size it is possible to provide a practical torch.

The distillation range for the fuel is from about 38° F. where approximately no distillation takes place to about 85° F. where 100% distillation is reached. Intermediate temperatures provide different percentages of distillation or evaporation according to the temperature.

The fuel is known as a self-pressurizing low pressure inflammable liquid, and its pressure range follows a curve from zero pressure at 38° F. to about twenty-five pounds per square inch at 100° F., about sixty-five pounds per square inch at 150° F., about one hundred thirty-five pounds per square inch at 200° F., and one hundred seventy pounds per square inch at 220° F. At this pressure the safety closure of the container is designed to blow off and release the contents.

The fuel is loaded as a liquid into the can at temperatures below 38° F. to avoid any pressure problem in loading and any tendency for leaking fuel gas. The loading is done with automatic equipment wherein a top metal cap 12 is applied over the open top of the can 11.

Cap 12 has a curved metal rim 13 adapted to fit over the rolled rim 14 of the can 11 and to be sealed therewith by a cap gasket 15 disposed and compressed therebetween.

The cap 12 has a body extending downwardly within can 11 with its side walls crimped outwardly at 16 beneath the rolled rim 14 to hold the cap in place.

Cap 12 also has a central opening with an upwardly extending neck flange 17 into which a grommet 18 of neoprene or the like is compressed and secured.

Grommet 18 has an enlarged inner end into which the upper flanged end of a dip tube 19 is secured, and an enlarged upper outer end with a circular central recess 20 extending downwardly from the top and connected to the upper end of the dip tube 19 by a slit 21 axially of the grommet. Slit 21 is normally closed by the compression of the central portion of the grommet in flange 17.

The grommet 18 is of a freeze-resistant neoprene or other suitable resilient sealing material which will heat soften at approximately 200° F. and blow out of cap 12, thereby constituting a safety release for can 11. The fuel employed is such as to release relatively quietly at this temperature and the corresponding pressures and without explosive effect, whereas if it were permitted to rise to three hundred pounds per square inch gauge pressure the can 11 might explode violently. Such considerations are desirable where a cartridge 2 of fuel might accidentally be disposed in a fire. Since the cartridge never contains a combustible or explosive mixture of fuel and air there is substantially no danger when the cartridge bursts or the cap 12 blows out, and should

a leak occur at room temperature the vaporization would be so slow in the open atmosphere as to present very little danger.

The material of grommet 18 should be of high resilience and toughness and preferably low in sulphur content to prevent any tendency of the grommet to tear at the upper edge of flange 17.

For the purpose of bleeding liquid fuel from the can a dip tube 19 extends to the bottom of can 11 and has its inner end open at one corner of the can so that it can be kept in the liquid fuel to nearly the last drop of liquid in the can.

The cartridge 2 is adapted to be filled to approximately three-quarters of its volume with liquid fuel and to retain the fuel under pressures corresponding to temperatures encountered in storage, transportation and handling. Only in the event of emergencies apart from normal usage, such as an external fire heating the cartridge to above 200° F., will it release its contents.

The valve assembly 3, which is adapted to be assembled with a fuel cartridge 2, comprises a metal body 22 having a downwardly extending circular flange or skirt 23 adapted to receive the outer head of grommet 18 and to seal thereagainst, an upwardly extending circular flange 24 threaded on the outside and adapted to be coupled to the burner 4, and a laterally extending circular flange 25 threaded internally and externally and adapted to receive the stem 26 of a manual valve 27.

The body 22 carries the bleeder device 28 centrally of skirt 23 and adapted to enter downwardly through grommet 18 into dip tube 19 for the release of fuel to the valve 27 and from thence to the burner 4.

The bleeder device 28 consists of a hollow tube open at the top end and closed at the bottom end except for a small side inlet port 29 near the bottom end. The tube 28 is carried vertically in a plug 30 fitting tightly upwardly inside skirt 23 and is of sufficient downward length to enter axially through grommet 18 separating the material thereof at slit 21 and to dispose inlet port 29 within the upper end of dip tube 19.

The plug 30 has a circumferentially grooved tapered shank 31 extending downwardly about the hollow tube 28 and adapted to enter recess 20 in the top of grommet 18 and to seal against the head of the grommet by expanding the same outwardly into pressure engagement with skirt 23.

The shroud 7 is secured upon lower skirt 23 between a shoulder 32 of the body 22 and a nut 33 threaded upon the skirt so that the cartridge 2 is securely held in sealed relation to the valve body.

The valve assembly 3 is sealed to cartridge 2 at three points: (1) where tube 28 passes through slit 21 in the region of cap flange 17, (2) where skirt 23 confines against the outer circumference of the outer head of grommet 18, and (3) where tapered shank 31 enters the top of grommet 18 and seals thereagainst.

Once a fuel cartridge 2 has been assembled with the valve assembly 3 and clamp 9 sprung home beneath the cartridge and base 5, the seals are maintained against fuel leakage for the operative life of the fuel in the cartridge. In the event it becomes desirable to remove a cartridge 2 from valve assembly 3 prior to the exhaustion of fuel from can 11, this may be done and slit 21 in grommet bud 18 will normally close and seal itself against fluid escape from the can. For this purpose it is desirable to employ a grom-

met material that will not set too quickly after opening thereof and that will retain its resilience over a reasonable period of time. Ordinarily, except under emergency conditions, it is inadvisable to remove a cartridge prior to exhaustion of its fuel, if the assembly has resulted in a setting of the grommet material sufficient to prevent closing of slit 21 upon removal of tube 28 therefrom.

The upper end of tube 28 leads to a recess 34 above plug 30 and from thence to a passage 35 extending upwardly to a transverse passage 36 axially aligned with valve stem 26. A frustoconical shoulder 37 in passage 36 receives a conical pointed inner end 38 of valve stem 26 to effect closure of passage 36, thereby constituting the valve shutoff of fuel for the torch.

The valve stem 26 is threaded into the flange 25 and is sealed at its outer end by a packing washer 39 abutting the end of flange 25, and a packing nut 40 threaded upon the flange and compressing the packing 39 against stem 26.

The inner end portion of stem 26 is of smaller diameter than the threaded outer end portion and carries a throttling valve washer 41 disposed on the stem between a retainer ring 42 and a stiff coil spring 43, the latter having its outer end engaging a shoulder 44 on the stem 26.

The washer 41 has a skirt 45 extending inwardly and adapted to abut a flat shoulder 46 in the valve body 22 surrounding the valve 27 to provide a throttling valve 47 which is normally closed by spring 43.

When valve stem 26 is threaded outwardly initially to open valve 27, spring 43 retains valve 47 closed except for normal tolerance abutment conditions which provides for about a thousandth of an inch crevice at various locations around the circumference whereby liquid fuel passing through valve 27 is confined and released at such rate as to gasify as it passes valve 47 for initial lighting of the torch.

The gas passes from around valve 47 to a vertical passage 48 in valve body 22 and from thence to the space surrounded by coupling flange 24.

The washer 41 should be sealed against stem 26 by means of a seal washer 49 and retainer washer 50 therefor disposed between throttle washer 41 and the inner end of spring 43.

In operation, after the torch is initially lighted the valve stem 26 may be threaded outwardly of valve body 22 by manual knob 51 on the outer end of the stem, to open both valves 27 and 47 wide. Liquid fuel will then pass upwardly to the burner assembly 4 and will be vaporized into a gaseous fuel before it reaches the burner 52 by heat passing downwardly along the burner tube 53.

The burner assembly 4 comprises the burner 52 which is shown as a blowtorch burner, a fuel supply riser tube 53 carrying the burner at its upper end, and a coupling nut 54 at the lower end of tube 53 threaded upon upper flange 24 of valve body 22.

A tapered ferrule 55 surrounds riser tube 53 adjacent its lower end and seals against the inside of flange 24 when nut 54 is threaded home upon the flange.

The riser tube 53 is bent at a convenient angle at its upper end for determination of the direction of burner 52 and its flame in use.

A riser insert 56 extends upwardly centrally in tube 53 to reduce the cross section of the opening in the tube and compel the fuel to pass in contact with the walls of the tube to thereby absorb

heat and gasify in its passage upwardly to burner 52.

A cotton filter and screen 57 supports insert 56 and is in turn supported in the lower end of riser tube 53 by a retaining ring 58.

The screen 57 and its filter tends to effect a gasification of the liquid fuel at this point when valves 27 and 47 have been opened and provided there is sufficient heat input to accomplish the same. In long periods of operation of the torch 10 the gasification point tends to occur at or close to the filter screen 57.

The burner 52 may comprise various types of torch or burner heads, that shown in Fig. 9 being a usual type of torch construction for blowtorches. In the illustration, Fig. 9, burner 52 comprises a cylindrical body threaded upon the outer end of riser tube 53 and having an orifice insert 58 at the end of tube 53 to direct a very fine axial stream of fuel into the burner from the tube.

A burner head 59 is threaded upon the outer end of the body 52 and has the usual baffle, pilot and flame outlet structures which need not be described herein. Primary air is admitted at the 25 discharge point or orifice 58 by means of a plurality of lateral openings 60 extending radially through the burner 52 to the mixing chamber therein.

The burner 52' illustrated in Fig. 10 is of the gas generating type wherein the liquid fuel from riser 53' is forced through small radial holes 61 in the upper end of tube 53' by reason of a plug 62 closing the end of the tube. The fuel passing through holes 61 follows the circumferential groove 63 in the outer surface of tube 53' to generating tube 64 which passes on the outside of the burner upwardly along the burner body 65 to a shoulder in the head 66 of the burner, thence around the burner in a groove 67 between the burner head and body 65 and in close metal to metal heat conductive contact therewith, and thence back down the outside of the burner body to a hollow jet head 68 in the base of the burner where the fuel is jetted axially through an orifice into the burner body. The burner body 65 is cylindrical and is conically enlarged at the head or discharge end thereof. Primary air is admitted at the discharge point of the orifice in jet head 68 by means of a plurality of lateral openings 69 extending radially through the burner body 65.

Various types of burner assemblies 4 may be employed depending upon the service desired, and a torch will be sold with several different types of burners for selection in service and each of which is designed to burn the specified blended fuel efficiently without air adjustment.

The portable torch is adapted for instant lighting by reason of the throttle valve 47 operative upon initial opening of the shutoff valve 27 to pass only a limited amount of gaseous fuel to the burner. After about sixty seconds of burning there is sufficient heat in the burner to permit manual opening of throttle valve 47 passing liquid fuel to the riser tube 53 where it is gasified upon its way to the burner.

This dual valve operation may be attained by the use of the dual valve of Fig. 7 or the valve illustrated in Fig. 8 wherein the spring 43 acts against the washer 44' on the floating valve stem 38'. The movement of valve stem 26' provides dual valve operation first as a shut-off valve and thereafter as a throttle valve when stem 38' is spring-pressed against valve seat 37. However, the illustrated construction of Fig. 7 has been 70 75

found the most satisfactory since it provides a wide lag between initial opening of valve 27 and final opening of throttle valve 47. Various valve constructions may be employed to provide the dual valve function described.

The mass of the valve body 22 provides sufficient residual heat capacity to effect gasification of the small amount of liquid fuel discharging past valve 47 during initial lighting of the burner.

The liquid fuel employed is one which tends to vaporize as it leaks through small ports of the order of one or two thousandths of an inch in cross section due both to the residual heat present in the metal body of the valve and the drop in pressure on the fuel. Consequently, it is possible to provide an initial lighting gasification by means of throttle valve 47, and to control subsequent gasification by the filter and screen 57.

By having the dip tube 19 extend to the bottom of can 11, the pressure is kept more constant since the gas at the top of can 11 is retained entrapped to supply the desired pressure upon the liquid fuel. Where the gas in the top of can 11 is supplied directly to the burner, as where no dip tube 19 is employed, it is necessary to supply more heat to the walls of can 11 to effect a boiling of the liquid fuel therein and thereby replenish the gas.

Furthermore, use of the gas at the top of can 11 is apt to result in initially utilizing the lighter hydrocarbon content of the blended fuel, making the B. t. u. output of the burner vary over the life of a cartridge of fuel. In the present construction the blended liquid is forced upwardly of dip tube 19 and to the burner, making a uniform fuel content throughout substantially the entire life of the fuel in a cartridge. The more constant pressure and fuel consistency eliminates the necessity of adjusting the air supply at the torch head during operation.

The torch is normally operated with valves 27 and 47 wide open. Should the gas pressure be lower than desirable, as when the room temperature is below normal, the hand of the operator on the exposed can 11 will serve to increase the pressure by supplying heat to the can. Should the pressure be higher than desired the operator should remove as much of his hand as possible from direct contact with can 11.

While the construction is illustrated as a blowtorch, it will be understood that equivalent application of the invention may be made to stoves and other types of burners. For this purpose wherever the term "torch" or "blowtorch" is used herein it is intended to include any equivalent burner where otherwise applicable.

The exact construction employed may vary and the invention may have various embodiments within the scope of the accompanying claims particularly pointing out and distinctly claiming the subject matter regarded as the invention.

I claim:

1. A portable blowtorch or the like, comprising a container of low pressure inflammable blended petroleum hydrocarbon liquid fuel composition having self-pressurizing characteristics at temperatures above about 38° F., said container being exposed for manual grasping with the hand of the operator to provide an initial pressure therein regardless of the surrounding temperature to feed liquid fuel therefrom, a valve head assembled with said container, a dip tube connecting with the valve head and extending into the liquid fuel of the container to bleed liquid fuel therefrom and retain within the container the initial

gas pressure without substantial diminution by withdrawal of the liquid fuel therefrom, and a torch burner head connected to said valve head and having a fuel passage and port therein adapted to transmit gaseous fuel to a burner flame at rates capable of providing maximum burner operation, said valve head comprising a body having a passage providing communication from said dip tube to said burner head and a valve seat encircling said passage, a valve member movable selectively within said body to positions opening and closing the passage therein and having an abutment fixed thereon to move therewith, said valve member including a relatively movable throttling element carried thereby, and spring means between said throttling element and said valve member to bias said throttling element against said valve seat, said throttling element and valve seat having irregular mating surfaces providing at normal spring pressures thereon a plurality of minute crevices restricting the passage of fuel between the same to allow only the passage of gaseous fuel through the valve head when said valve member is initially released from closed position, said valve member and throttling valve element controlling the passage of said valve head in series relationship, and said abutment being disposed upon movement with said valve member to engage said throttle valve element and effect movement of the latter away from said valve seat to open the passage of said valve head for full burner operation and provide for unrestricted passage of liquid fuel toward said burner port after initial starting of the burner and during normal operation thereof whereby the heat supplied from the burner to the metal surrounding the fuel passage approaching the port effects gasification of the fuel at rates adapted for maximum burner operations.

2. The blowtorch of claim 1 in which the fuel container is a replaceable cartridge having a top closure adapted to be opened by the valve head when assembled therewith, and the dip tube is secured to the top of the container to provide for bleeding of the liquid fuel through the opening effected by the valve head.

3. The blowtorch of claim 1 in which the fuel container is a replaceable cartridge having a top closure comprising at least in part a resilient grommet carrying the dip tube and having a neck confined under pressure with a normally closed axial split therethrough for receiving a fuel bleeding device of the valve head.

4. The blowtorch of claim 1 in which the fuel container is a replaceable cartridge having a top closure comprising at least in part a resilient grommet carrying the dip tube and having a neck confined under pressure with a normally closed axial portion for receiving a fuel bleeding device of the valve head, and said grommet having an upper head for sealing with the valve head, the upper head having a central recess in its top for receiving a tapered shoulder on the bleeding device and the outer circumference of the upper head being adapted to be confined in a recess in the valve head.

5. The blowtorch of claim 1 in which the fuel container is a replaceable cartridge having a top closure comprising at least in part a resilient grommet carrying the dip tube and having a neck confined under pressure with a normally closed axial slit therethrough for receiving a fuel bleeding device of the valve head, said grommet being of a heat softening rubber-like material serving

as a safety valve for the cartridge whereby pressures and temperatures above normal will effect a discharge of the grommet from the cartridge.

6. The blowtorch of claim 1 in which the fuel container constitutes a replaceable cartridge and the valve head is carried by a shroud for securing the container and valve head in assembled relation, the shroud comprising upper and lower clamping members adapted to receive and confine the ends of the cartridge, the upper member carrying the valve head and the lower member constituting a base adapted to support the cartridge on end with the torch upright, a strap rigidly secured to one of said members and hingedly secured to the other of said members to determine the space therebetween when the members are disposed in clamping position upon a cartridge, and a strap hingedly secured to the upper member and having a bent spring end adapted to pass beneath said lower member and to interlock therewith to secure the same clamped against the cartridge.

7. A portable blowtorch and the like comprising a lightweight thin-walled disposable container adapted to be grasped by the hand of the operator to provide initial heat thereto, a low pressure inflammable blended petroleum hydrocarbon liquid fuel in said container and having an initial atmospheric pressure vaporization point for the most volatile constituent of the blend substantially below normal room temperature and a final atmospheric pressure vaporization point for the least volatile constituent of the blend substantially above normal room temperature, said fuel blend being substantially free from undue separation by stratification and being capable of developing a gage pressure of the order of twenty-five pounds per square inch at 100° F., said separate fuel constituents requiring different air ratios for efficient burning thereof, a valve head removably assembled with the top of said container, conduit means to conduct liquid fuel to said valve head from near the bottom of the container whereby the blended liquid fuel is delivered to the valve head under the substantially constant pressure of gas above the liquid in the container at normal operating temperatures, valve means in said valve head, a burner having fixed air inlet means to effect efficient burning of the blended gaseous fuel, and means connecting said burner to said valve head and adapted to supply fuel to the burner, said means and said valve head being adapted to supply heat to the liquid fuel as it passes therethrough to gasify the same at the rate of consumption therefore determined by the capacity of said burner and the opening of the valve in said valve head, whereby operation of the burner effects continued progressive gasification of all fractions of the liquid fuel in its approach to the burner and whereby substantially all of the blended liquid fuel in the container may be burned efficiently by said burner without adjustment of the air supply thereto.

8. The construction of claim 7 in which the means to conduct fuel to the valve head from near the bottom of the container comprises a dip tube in the container, a puncturable member sealing the upper end of the dip tube, and a bleeder tube carried by the valve head and adapted to pierce said member and to enter the upper end of said dip tube to receive fuel therefrom when said valve head is assembled with the container.

9. The construction of claim 7 in which the most volatile major constituent of the fuel is

11

normal butane having an initial vaporization point in the blend of about 38° F., and the least volatile major constituent of the fuel is isopentane having a final vaporization point in the blend of about 85° F.

10. The construction of claim 7 in which the valve head comprises a body of metal of substantial mass having a valve seat and a valve passage therethrough and substantial residual heat capacity, and a movable valve means therein to control the flow of fuel through said passage, said valve means cooperating with said valve seat and being adjustable to limit the passage of liquid fuel during starting of the burner wherein the residual heat of the valve body vaporizes the small amount of liquid fuel passing the valve means and thereafter being adjustable to provide an open passage for the flow of fuel to the burner during continued operation of the torch and in which the back pressure of the gas in the zone of vaporization confines and restricts the flow of liquid fuel to that necessary for supplying the burner with gaseous fuel.

11. The construction of claim 7 in which the fuel is substantially of the following composition:

	Per cent
Normal butane	53
Isobutane	2
Isopentane	43
Normal pentane	2

12

12. The construction of claim 7 in which the means connecting the burner to the valve head comprises a riser tube containing a screen filter, and a riser insert reducing the passage in the tube and increasing heat transfer to the fuel rising in the tube whereby the vaporization of the fuel is assured prior to its reaching the burner.

13. The construction of claim 7 in which said burner comprises a burner body, fuel conduit means in heat conductive relation to said body, means connecting said conduit means to receive fuel from said specified means connecting the burner to the valve head, and orifice means discharging gaseous fuel from said fuel conduit means into said burner body.
